Primary Examiner — Keith J Wilson(74) *Attorney, Agent, or Firm* — Merchant & Gould P.C.(57) **CLAIM**

An ornamental design for a handheld showerhead mount as shown and described.

DESCRIPTION

FIG. 1 is a top perspective view of a handheld showerhead mount according to a new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

The portions depicted in broken lines form no part of the claimed design.
